AUTOMATIC INFLATOR FOR LIFE PRESERVING APPARATUS

Harry L. Pontious, Los Angeles, and Edward L. Caustin, Hawthorne, Calif., assignors to North American Aviation, Inc.

Application January 18, 1956, Serial No. 559,804

2 Claims. (Cl. 222—5)

This invention relates to an inflating device for floatation equipment and in particular relates to an inflator for life preserving equipment which operates quickly and automatically to inflate such equipment upon immersion in water.

Many types of automatic life preserver inflators are known in the art. Most of these use various triggering devices for puncturing a pressurized gas cartridge and causing the gas contained therein to be released to inflate the preserver. Some such devices utilize a water soluble tablet for holding the trigger mechanism in an inoperative position until the tablet is dissolved upon contact with water and the trigger mechanism is thereby actuated to liberate gas from the pressurized cartridge. Other types have a trigger mechanism that is float operated and thus have the disadvantage of being position sensitive. Still other devices use a pressure operated triggering means that requires the generation of a considerable gas pressure for its operation. Some of the latter devices also have the disadvantage of requiring submergence to an appreciable predetermined depth in order to commence actuation of the gas generating means. In addition to the various special requirements, some of which are set out above and which are necessary to the operation of many of these triggering devices, most of these mechanisms do not operate with sufficient rapidity to render them fully effective for inflating life preserving equipment in the shortest possible time.

The present invention contemplates the use of a dependable, gas actuated, spring-loaded trigger mechanism for use with the standard type carbon dioxide cartridge and holder in use by U.S. armed forces. It utilizes a fast acting chemical tablet designed to produce sufficient non-combustible gas, upon contact with a single drop of water, to be able to operate the trigger mechanism within a few seconds. The triggering mechanism is so lightweight and compact as to be able to fit into the same pocket on the Armed Forces' "Mae West" type life preserver that is presently used for storing only the manually operated gas cartridge and holder.

Accordingly it is the principal object of this invention to provide a reliable, positive acting means for automatically inflating life preserving apparatus upon immersion in water.

It is another object of this invention to provide an inflator that is not dependent for actuation upon its position or depth of submersion in the water.

It is also an object of this invention to provide an automatic inflator mechanism adapted for use with existing standard types of manually operated gas cartridges and cartridge holders.

It is a further object to provide an automatic inflator mechanism that will function upon the application of a slight amount of water to the gas generation means of the mechanism.

A still further object of this invention is to provide an inflating device which is compact, light-weight, and de-

pendable in operation and which may be comfortably worn with a life preserver of the "Mae West" type.

These and other objects and advantages of the present invention will become apparent to those skilled in the art after reading the present specification and the accompanying drawings forming a part hereof, in which:

Fig. 1 is a side elevational view of the automatic inflator of this invention showing the plunger and trigger lever in a fired position.

Fig. 2 is a top plan view of the automatic inflator as connected to an inflatable life preserver.

Fig. 3 is a side elevational view, partly in cross section showing the spring loaded plunger and the cartridge piercing pin mechanism, all in a cocked position.

Fig. 4 is a fragmentary sectional view taken in the plane of line 4—4 in Fig. 2 showing the piston operated latching mechanism in a cocked position prior to activation.

Fig. 5 is a fragmentary transverse sectional view taken in the plane of line 5—5 in Fig. 1 showing the piston operated latching mechanism in a fired position with the spring biased plunger released for movement downwardly.

Fig. 6 is an elevational view of the flexible flapper inlet valve.

Referring specifically to the drawings, wherein like reference characters have been used throughout the several views to designate like parts, and referring at first to Fig. 2 numeral 10 designates an inflatable life preserver in the form of a vest or "Mae West" type of life jacket of standard construction. A commercially available cartridge 11, shown in Fig. 3, is charged with a compressed gas, such as carbon dioxide, and sealed by a puncturable disk 16. Gas cartridge 11 is fitted within a standard commercially available holder 12 having a threaded engaged head 13 removable for replacement of spent cartridges. A piercing pin or element 14 is longitudinally slidably relative to cartridge 11 whereby it may be made to puncture disk 16 and release the pressurized gas into casing chamber 47 which communicates with the interior of the life preserver through passage 34. A bell crank type lever or trigger 15 is pivotally mounted at the lower end of holder 12 and has a cam portion 48 bearing on the lower end of piercing pin 14, with the outer end 49 of lever 15 being manually operable to force spring loaded

pin 14 into piercing relationship with cartridge 11 and thereby release the compressed gas and inflate the life preserver. The above described cartridge and holder are of the conventional manually operated type standard with the U.S. Armed Forces.

In accordance with the present invention there is provided a trigger mechanism 17 for automatically actuating lever 15 upon immersion in water and adapted to be detachably clamped to the standard cartridge holder 12. Trigger mechanism 17 comprises an elongated housing

18 having transversely extending C-clamps 55 spaced along the housing. Complementary C-clamps 56 are adapted to be bolted to matching clamps 55 and coact therewith to attach housing 18 to holder 12. A loosely fitting plunger 19 is slidably mounted in cylindrical bore 20 for longitudinal movement therein. The lower end of bore 20 is closed by end wall 21 centrally apertured for passage of plunger 19. The upper end of housing 18 is interiorly threaded for closure by threaded plug 33. Plunger 19 has an axially aligned counterbore 22 extending downwardly from the upper end thereof.

A button 23 has a stem threadedly engaging the lower end of the plunger and bearing on the outer end 49 of lever 15. By removing button 23 and plug 33 plunger 19 may be withdrawn from housing 18 for cleaning after immersion in water. A shoulder or lip 27 is formed on the exterior of the plunger at the upper end thereof.

70

Compression spring 28 is seated on an interior shoulder (not shown) within counterbore 22 with the other end of the spring abutting spring retainer plug 33. Spring 28 thus tends to urge plunger 19 outwardly through aperture 30. This spring is of sufficient strength to force plunger 19 downwardly whereby lever 15 is actuated to drive pin 14 to puncture disk 16.

An integral hollow cylindrical boss 31, eccentrically offset from the longitudinal axis of bore 20, projects transversely from housing 18 near its upper end. Boss 31 is externally threaded for engagement with interiorly threaded cap 35 and forms therewith a piston chamber 37. Cap 35 compresses an O-ring 53 against shoulder 54 to provide a pressure-tight seal for chamber 37. Cap 35 also has an axially concentric inlet port 36 in the cap end thereof, with a removable flexible flapper valve 40 held in position against the inner surface of the cap end by annular retaining ring 41.

The entrance passageway 24 leading to port 36 in the end of the cap has a smooth round edged substantially tapering configuration forming an airfoil like surface. This airfoil shaped surface has an important effect on the prompt actuation of the flapper valve. When moved relative to the water this surface acts similarly to the diverging portion of a venturi tube, so that as trigger mechanism 17 is dropped into the water either vertically or with port 36 in an upwardly facing direction, water tends to flow over the airfoil-like surface and inwardly against flapper valve 40 thereby opening the valve and allowing water to flow into chamber 37 and contact chemical tablet 52. This venturi-like characteristic of passageway 24 insures prompt and positive operation of the flapper valve and causes the flow of water therethrough into chamber 37 under action of the hydrodynamic forces created by the flow of water over the airfoil-like surface. If the trigger mechanism 17 is tilted, upon entering the water, so that the passageway 24 and port 36 are facing downwardly from a horizontal plane, the flapper valve 40 will be directly contacted by the water and opened by the force of the impact thereon. Additionally valve 40 is of such a flexible resilient construction that it will be opened by an extremely small hydrostatic pressure thereon and need not be immersed to any considerable depth before it will open to admit the liquid. Thus it is evident that flexible flapper valve 40 will admit liquid into chamber 37 under the slightest hydrodynamic or hydrostatic pressure.

Upon actuation of the gas generation means valve 40 will close tightly and seal inlet port 36 under pressure of the gas generated within chamber 37. Any suitable material may be employed for the flapper valve but an oil resistant composition such as neoprene is particularly adapted for this purpose.

Cylindrical piston stem bore 42 extends from the inner end of chamber 37 transversely through housing 18 and substantially tangentially intersects and opens at 32 into bore 20 near one end thereof. Bore 42 is axially concentric with the extended longitudinal axis of chamber 37 but is offset or eccentric to the longitudinal axis of bore 20.

A piston 38 is reciprocably mounted in chamber 37 and has a peripheral groove 43 for a piston seal ring 44 seated therein. Piston seal ring 44 may be of any suitable material but is also preferably of an oil resistant material such as neoprene. Integral with piston 38 cylindrical piston stem 39 extends reciprocably into bore 42. With piston 38 in its outermost or "cocked" position end portion 46 of stem 39 projects tangentially into bore 20, near the edge thereof, and supports plunger 19 under shoulder 27 whereby downward movement of the spring biased plunger is restrained. However, at an intermediate location on stem 39, predetermined by the position of the integral piston and stem when it has been forced inwardly by the gas pressure generated, a portion 45 of the stem is reduced in diameter sufficiently to allow shoulder 27

of the plunger to clear the reduced portion when it is opposite bore 20.

Thus it is evident that stem 39 and integral piston 38 comprise a latching or restraining mechanism for retaining the spring biased plunger in a "cocked" position near the upper end of housing 18. Upon actuation of the piston inwardly toward the housing body under pressure of gas generated in piston chamber 37, the latching mechanism is released and spring 28 forces plunger 19 downwardly to actuate trigger lever 15 and thereby move piercing pin 14 to puncture disk 16 and release the gas compressed in cartridge 11.

Since the automatic operation of a life preserver inflating device is designed for situations wherein the person wearing or using the life preserver is unconscious or otherwise unable to operate the inflating device manually, speed in actuating the mechanism is of the utmost importance. Although any suitable chemical tablet may be used to generate a gas, in the preferred embodiment an effervescent tablet comprising 60% dry tartaric acid and 40% sodium bicarbonate is utilized. This tablet is ordinarily able to fire the inflator in less than ten seconds after contact with a single drop of water. This soda-acid type tablet liberates a non-toxic, non-combustible gas. This is an extremely important and desirable characteristic in view of the fact that life preserving equipment of this type must often be used in or around highly inflammable materials such as fuels floating on the surface of water in the vicinity of a damaged ship or aircraft. Most of the existing types of inflator mechanisms that depend on the generation of a gas for their operation utilize a calcium carbide tablet to form highly combustible acetylene gas upon contact with water. The use of such a combustible and inflammable gas is extremely dangerous in the above circumstances.

In operation the standard cartridge having the inflator mechanism of this invention securely attached thereto would normally be operated by the user by manually pulling down on pull cord 50 attached at the outer end of trigger 15 with a button 51 mounted on the end of the cord. This operation will move lever 15 to drive piercing pin 14 to puncture cartridge 11 and release the pressurized gas contained therein to inflate the connected and communicating "Mae West" or life preserver.

In the event the user has not manually inflated the life preserver shortly after being immersed the automatic trigger mechanism 14 will perform this function. Under the slightest hydrodynamic or hydrostatic pressure flapper valve 40 will open to admit water into chamber 37, chemical tablet 52 reacts with the water to effervesce and release a gas. The gas pressure generated in the chamber seals valve 40 against the interior of the end of cap 35. The gas pressure increases rapidly until it exerts a force on piston 38 sufficient to overcome the frictional force exerted by the shoulder 27 of the spring biased plunger on piston stem end portion 46. This required force is in the range of from 5 to 8 pounds. When this frictional force is exceeded piston 38 and integral piston stem 39 move inwardly and reduced piston stem portion 45 is thus positioned at a point opposite bore 20. This reduced portion 45 of the piston stem is of such size as to allow plunger shoulder 27 to pass by the reduced portion of the stem. When this occurs spring 28 drives plunger 19 and attached button 23 forcefully downwardly against the outer end 49 of trigger 15 and thus actuates piercing pin 14.

To cock the trigger mechanism piston 38 must be at its innermost position with reduced stem portion 45 opposite bore 20. Plunger 19 may then be forced up into bore 20 until plunger shoulder 27 is above piston stem 39. The stem is then pushed to the left, by means of projecting stem end portion 46, to its "cocked" position wherein the lower edge of shoulder 27 will bear on the top surface of end portion 46 and the piston is at its outermost position. Cap 35 is disengaged from boss 31 and a

chemical tablet 52 is inserted therein so as to be positioned between inlet valve 40 and piston 38 when the cap is threadedly replaced on the boss. Trigger 15 is then moved in a clockwise direction until the outer end 49 bears against plunger button 23. Upon removal of the spent cartridge from holder 12, insertion of a charged cartridge therein and replacement of holder head 13 the inflator unit is once more ready for automatic or manual operation.

While a particular embodiment of this invention has been illustrated and described herein, it will be apparent that various changes and modifications may be made in the construction and arrangement of the various parts without departing from the spirit and scope of this invention in its broader aspects or as defined in the following claims.

We claim:

1. An inflating device for pneumatic floatation apparatus for both automatic and manual actuation comprising a sealed inflation gas cartridge mounted in a holder having a relatively movable piercing element therein adapted to contact said cartridge and communicating with the floatation apparatus, a lever pivotally mounted on said holder having one end contacting said piercing element for actuating the same to puncture said cartridge, a housing having an axially extending bore therein open at one end in juxtaposition to said cartridge holder; a plunger slidably mounted in the axial bore in said housing having an outer end operatively contacting the other end of said lever; a spring in said housing biasing said plunger outwardly of the housing in an axial direction to pivot the lever and thereby actuate said piercing element; a body integral with said housing having a piston chamber therein normal to said housing axial bore, said housing having a cylindrical bore communicating with said piston chamber and axially coincident therewith extending through the housing and tangentially intersecting and communicating with said housing axial bore; a piston reciprocal in said piston chamber; a stem on said piston extending into the cylinder bore and forming a latch means retaining said plunger against axial movement by engaging the piston portion of said plunger when the piston is at one end of its travel, said piston stem having a reduced diameter portion permitting unlatching and axial movement of the spring biased plunger when the piston is positioned at the other end of its travel, said piston chamber having an opening permitting entrance of water therein and a flapper valve thereover adapted to close said opening when acted upon by gas pressure within said piston chamber; an effervescent tablet in said piston chamber capable of rapidly generating sufficient noncombustible gas upon contact with a slight amount of water to close said flapper valve and operate said piston to drive said stem latching means to an unlatched position whereby said lever may be pivoted by the spring biased plunger to actuate the piercing element; and means for actuating said piercing element manually.

2. An automatically and manually actuatable inflating device for pneumatic floatation apparatus comprising a sealed inflation gas cartridge mounted in a holder having a relatively movable piercing element therein adapted to contact said cartridge and communicating with the floatation apparatus; a lever pivotally mounted on said holder having one end contacting said piercing element and adapted to actuate the same to puncture said cartridge; a housing having an axially extending bore therein open at one end attached to said cartridge holder; a plunger slidably mounted in the axial bore in said housing having a piston portion and a reduced diameter piston rod portion, said piston rod portion extending exteriorly of the housing bore and having an end portion contacting the other end of the pivotally mounted lever; a spring in said housing biasing said plunger outwardly of the housing in an axial direction to pivot the lever and thereby actuate said piercing element; a body integral with said housing having a piston chamber therein normal to said housing axial bore; said housing having a cylindrical bore communicating with said piston chamber and axially coincident therewith extending through the housing and tangentially intersecting and communicating with said housing axial bore; a piston reciprocal in said piston chamber; a stem on said piston extending into said cylinder bore and forming a latch means retaining said plunger against axial movement by engaging the piston portion of said plunger when the piston is at one end of its travel, said piston stem having a reduced diameter portion permitting unlatching and axial movement of the spring biased plunger when the piston is positioned at the other end of its travel, said piston chamber having an opening therein with a venturi-like tapered entrance configuration for inducing flow therethrough upon relative movement of water past the inlet; a resilient flapper valve covering said inlet and adapted to open under the slightest water pressure and to close when acted upon by gas pressure within said piston chamber; and an effervescent tablet in said piston chamber capable of rapidly generating sufficient noncombustible gas upon contact with a slight amount of water to close said flapper valve and operate said piston to drive the stem latch means to an unlatched position whereby said lever may be pivoted by the spring biased plunger to actuate the piercing element, said effervescent tablet comprising essentially 60% dry tartaric acid and 40% sodium bicarbonate; and means for actuating said piercing element manually.
